METHOD OF FLARING TUBES

Wilhelm Beikmann, Hilden, Germany, assignor
to the firm Vereinigte Stahlwerke Aktiengesellschaft, Dusseldorf, Germany.

Application May 17, 1933, Serial No. 671,580
In Germany December 16, 1932

8 Claims. (Cl. 205—7)

This invention relates to a method and device for flaring tubes by drawing.

Flaring of tubes by drawing was carried out hitherto by supporting the tube to be drawn relative to a traverse and then drawing a plug of larger diameter through the tube from the free end thereof. This method suffers from the drawback that the tube during the drawing process is subjected to compressive strain in longitudinal direction so as to collapse easily. For this reason it is necessary to keep the strain low or to do the flaring while the tube is cold, and this explains why it is impossible to do any flaring worth mentioning.

It is the object of the invention to provide a method and means which make it possible to draw up tubes to a considerably greater extent by subjecting the tube during the drawing process to tensile stress by a suitable arrangement of its abutment. It will then be possible to work the tube while it is red hot and to carry out a relatively large amount of flaring in one operation. Furthermore, if devices according to the invention are provided in order to draw several conical plugs one behind the other and in one operation through the tube, an opportunity is afforded of attaining at one heating of the tube a degree of flaring that could not be economically produced hitherto.

By way of example, the invention is illustrated in the accompanying drawing, in which Figure 1 is a longitudinal section of a tube with flange prepared for drawing; Fig. 2, a longitudinal section of a tube having a pilger head; Fig. 3, a longitudinal section of a drawing device according to the invention; Fig. 3a is a partial plan view according to Fig. 3 showing especially the driving mechanism of the drawing rod, and Fig. 4, an end view of this device as seen from the side of the lifting table.

In order to carry out the method according to the invention a draw bench is provided with an abutment block carrying a draw plate a_1, a_2 divided on the plane of the axis. The half member a_1 of the draw plate is disposed in the lower fixed part of the abutment b , and the other half a_2 can swing with the top of the abutment c about the axis d parallel to the central axis. The tube r which is flared or enlarged at its end to the desired diameter by an upsetting press and provided with the flange f or the pilger head p and having previously been brought to drawing temperature is rolled from the side into the drawing frame whose upper half is turned up so as to be adjacent with the flange f or the pilger head

p to the lower half of the draw plate a_1, a_2 , whereupon the top half c of the frame is turned down together with the upper half a_2 of the draw plate. The conical drawing plugs s_1, s_2 with increasing outer diameter are ready and disposed on a table before the abutment block. They possess a bore through which the drawing rod z is pushed, and after the latter has been passed through these bores, the plugs s_1, s_2 are connected with the rod z by the wedges k_1, k_2 and drawn through the tube r in one operation or singly. When the desired extent of flaring has been attained, the top of the abutment block is turned up and the tube removed from the device.

The table t carrying the prepared plugs s_1, s_2 can be raised and lowered to permit accurate adjustment of the plugs relative to the center of the drawing device, the adjustment being carried out by mechanical, hydraulic or pneumatic means. Moreover, to facilitate the insertion of the mandrel bar z in the bores of the plugs s_1, s_2 , between the abutment block b, c and the table t a roll e capable of being raised and lowered is provided, the stroke of the roll e being arranged so as to clear the way for the passage of the plugs s_1, s_2 .

I claim:—

1. Device for flaring tubes, comprising a bed, an annular bearing having a supporting flange on one side arranged on said bed and divided transversely to its axis, a rod displaceably arranged in the axis of the annular bearing, cylindrical plugs arranged on the rod and secured by wedges, said plugs having conical surfaces, a table adjustable as to height for supporting the plugs, and a driving device arranged on the side turned away from the supporting flange of the annular bearing and engaging the end of the drawing rod.

2. Device for flaring tubes, comprising a bed, a block disposed on the bed and provided with a cylindrical bore, said block being on the radial plane divided into two parts and capable of swinging with one part about an axis parallel to the axis of the bore, two halves of a ring member having a flange on one side, each half being disposed in the bore of one part of said block, a rod arranged in the axis of the bore or ring member, a carriage arranged on the side turned away from the flange of the ring member and to which the rod is attached so as to be displaceable in its axis, a driving device engaging the carriage, cylindrical plugs of different diameter provided with conical surfaces, said plugs being pushed upon said rod by means of bores one behind the other and secured by wedges thereto, a table adjustable as to height supporting the underside of

the plugs, and a roll adjustable as to height for supporting the rod.

3. A method of making seamless tubes, the outer diameter of which is so great as compared with the small wall thickness that it cannot be attained by the mere rolling process, characterized by the fact that the final measurement is effected by drawing a mandrel through the tube by flaring to the greater outer diameter, the tubes being held on the side of the mandrel inlet.

4. A method according to claim 3, characterized by the fact that the tube is flared on the side of the mandrel inlet and is provided on the outer edge of this enlargement with a projection where-
15 by the workpiece is secured to an abutment when flaring while the enlargement itself extends into the abutment.

5. A method according to claim 3 for producing socket pipes, characterized by the fact that the inlet end for the flaring tools is flared in the form of the socket head and bears therewith against the abutment.

6. A method according to claim 3, characterized by the fact that a plurality of drawing plugs with an increasing diameter are drawn through the tube without re-heating the latter.

7. A method of flaring tubes having one end enlarged and flanged consisting in heating the main portion of the tube, then clamping and holding only the enlarged and flanged end thereof so as to support the tube and prevent axial displacement thereof, then repeatedly drawing pressure applying members of increasing diameter axially through the major portion of the tube from the enlarged end while the latter is in a heated state to gradually and uniformly increase 10 the cross sectional area thereof.

8. A method of making seamless tubes of the type possessing an outer diameter so great as compared with the small wall thickness that it cannot be obtained by a mere rolling process consist- 15 ing in enlarging and flanging one end of a tube when in a cold state, then heating the main portion of the tube only, then clamping and holding the enlarged end of the tube only so as to support the same and prevent axial displacement 20 thereof, and then repeatedly drawing pressure applying members of increasing diameter axially through the tube from the enlarged end while the latter is in a heated state to gradually and uniformly increase the cross sectional area thereof. 25

WILHELM BEIKMANN.
